(57) **CLAIM**

The ornamental design for a merchandise attachment with RFID transponder, as shown and described.

DESCRIPTION

FIG. 1 is an isometric view of a merchandise attachment with RFID transponder, showing my design; and

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an isometric view of the claimed design shown in an alternate position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

In the drawings, the broken lines depict perforations, which form part of the claimed design.
